UNITED STATES PATENT OFFICE.

LEONARD L. BROWN, OF CLIFTON FORGE, VIRGINIA, ASSIGNOR OF ONE-HALF TO JOHN W. BEAR, OF CLIFTON FORGE, VIRGINIA.

AUTOMATIC EMERGENCY FLAGGING-MACHINE.

1,093,824.

Specification of Letters Patent. Patented Apr. 21, 1914.

Application filed September 14, 1912. Serial No. 720,376.

To all whom it may concern:

Be it known that I, LEONARD L. BROWN, a citizen of the United States of America, residing at Clifton Forge, in the county of 5 Alleghany and State of Virginia, have invented certain new and useful Improvements in Automatic Emergency Flagging-Machines, of which the following is a specification, reference being had therein to the accompanying drawing.

This invention relates to automatic stopping devices to be applied to a railroad rail, whereby the brakes of a train will be automatically operated in case the engineer 15 should not notice the signal of a flagman.

The present invention is especially adapted to be carried by a flagman when he is sent back to warn an approaching train, and is adapted to be applied to the rail of 20 a track in such a manner as to be picked up from the rail as soon as an instrument carried by the pilot of a locomotive should strike the signaling device.

The object of this invention is, therefore, 25 to produce a simple and efficient mechanism which will automatically throw the brakes of a train, providing the engineer should disregard the signal of the brakeman, or should it be impossible for him, owing to the condition of the weather, to distinguish the signal 30 of the brakeman.

Other objects and advantages of the present invention will appear throughout the following specification and claims.

35 In the drawings: Figure 1 is top plan view of the device as applied to a portion of the rail, and to the pilot of a locomotive. Fig. 2 is a side elevation of the device as illustrated in Fig. 1. Fig. 3 is a detail perspective of 40 the receiving apparatus carried by the pilot of the locomotive. Fig. 4 is a detail perspective of the track instrument adapted to be attached to the rails of a track. Fig. 5 is a fragmentary sectional view of a portion 45 of the receiving apparatus and the track instrument, showing the manner in which the track instrument is gripped by the receiving apparatus after the forward head has been driven into the receiving apparatus. Fig. 6 is a fragmentary sectional view of the rear 50 end of the track instrument, showing the manner of connecting the frame to the base of the instrument. Fig. 7 is a fragmentary sectional view of one end of the framework 55 of the receiving instrument, showing the

manner in which the sliding doors travel over the side of the framework. Fig. 8 is a section taken on line 8—8, Fig. 5. Fig. 9 is a detail perspective of the base of the track instrument, showing the construction of the 60 device which is adapted to hold the track instrument in engagement with the rail.

By referring to the drawings, it will be seen that the present device comprises a receiving apparatus and a track instrument or 65 apparatus. The receiving apparatus is carried by the pilot of the locomotive and comprises a framework 1 having an upwardly-extending arm 2, which arm is connected to a depending bracket 3 carried by the pilot 4 70 of the locomotive. Bolts 5 pass through the bracket 3 and through the apertures 6 formed in the arm 2 for rigidly supporting the receiving apparatus in an operative position. The receiving apparatus projects 75 through one side of the pilot as illustrated clearly in Figs. 1 and 2, and the outer face of the receiving apparatus slants at an angle to the side of the pilot so as to present the least possible resistance to any objects 80 which the pilot might pick up while the locomotive is traveling. Owing to the angle at which the receiving apparatus extends, it will be seen that if the pilot should strike any foreign object the object would glance 85 off of the side of the receiving apparatus without affecting the brakes of the locomotive, owing to the fact that the mechanism for operating the brakes of the locomotive is 90 shielded behind the receiving apparatus. 90

The framework 1 is provided at its front end with a pair of diverging fingers 7, which fingers terminate in upwardly-extending parallel arms 8. These arms are connected at their lower ends by means of a transversely-extending truss member 9, and at their upper ends by means of a transversely-extending truss member 10, which truss members 9 and 10 rigidly brace the arms 8 together. 100

The receiving apparatus or mechanism comprises a pair of receiving jaws 11, the lower jaw of which is fixedly secured to the parallel arms 8 by having its side edges straddling the side members and secured to 105 the parallel arms of the side members by means of rivets 12, as clearly illustrated in Fig. 3. The upper jaw is formed similarly to the lower jaw, and has its side edges formed to constitute substantially U-shaped 110

edges for overhanging the parallel arms 8, thereby constituting a substantially tongue-and-groove joint. The upper jaw 11 is freely slideable upon the parallel arms 8 so as to yield upwardly when the track instrument strikes the jaws 11. Both of the jaws 11 are so formed in their center as to produce a pocket constituting an aperture 13, having gradual, inwardly sloping walls 14 for directing the head of the track instrument toward the aperture 13 in case the head should not strike exactly the center of the aperture 13. The upper jaw 11 carries a pair of upwardly-extending spring-engaging frames 15 which have their lower ends fixedly secured to the upper jaw as indicated at 16. The upper ends of the spring-engaging frames 15 are bent so as to produce overhanging ends 17 for engaging the coil springs 18, which coil springs are connected at their lower ends to laterally-extending integral arms 19 carried by the parallel arms 8 of the framework 1. These spring-engaging frames 15 are so formed as to have free vertical sliding movement upon the parallel arms 8 so as to allow the upper jaw 11 of the receiving apparatus to move freely upward so as to admit the head of the track receiving instrument hereinafter described.

When applying the present device to a locomotive, a branch pipe 20 is connected to the main pipe line 21 which is connected with the air brake mechanism, and this branch pipe 20 is provided with a valve 22 having a projecting arm 23, which arm is adapted to open and close the valve 22 when the arm 23 is swung. The arm 23 is provided with a projecting end 24, which projecting end 24 is adapted to be engaged by the upper end 25 of the valve-throwing finger 26. This valve-throwing finger 26 is connected to an angle bracket 27 carried by the upper jaw 11 by means of a connecting joint 28. It will be seen that as the track instrument illustrated in Figs. 2 and 4, and hereinafter described, enters the aperture 13, the upper jaw 11 will move upwardly and carry the valve-throwing finger 26 upwardly, thereby raising the arm 23 and causing the valve 22 to operate, thereby applying the air brakes and accomplishing the desired result by bringing the locomotive or train to a stop.

As previously stated, a track instrument as illustrated in Fig. 4 is employed in connection with the receiving apparatus above described, and this track instrument comprises a base section 29, which section 29 is substantially U-shaped in cross section so as to overhang the tread of a rail. The base 29 is provided, at its rear end, with a raised rib 30, in which rib 30 is formed a plurality of notches 31 for facilitating the adjustment of the track instrument at different angles for the purpose of striking the re-

ceiving apparatus carried by the locomotive at the desired point, especially when the track instrument is set on a curve. The base 29 is also provided with a forwardly-projecting tongue 32 which lies flat upon the upper face of the tread of a rail, and intermediate the ends of the base 29 is formed a pair of oppositely-extending angle arms 33. Wire gripping triggers 34 are pivotally secured to the outer ends of these arms 33 as indicated at 35, and these triggers 34 comprise upwardly-extending arms 36, which upwardly-extending arms 36 fit in the bifurcated laterally-extending feet 37 of the framework 38 of the track instrument. The trigger arms 34 are also provided with inwardly projecting fingers 39, which fingers are adapted to engage the edges of the fish plates 40 of the rails 41, so as to hold the track instrument in a set position upon the rail and prevent the longitudinal movement of the instrument relative to the rail.

The frame 38 of the track instrument comprises a pair of parallel arms 42, and by having its laterally-extending bifurcated feet 37 engaging the upwardly-extending fingers 36 of the trigger arms 34, it will be seen that the frame 38 will be firmly held in engagement with the rail.

A releasing arm 43 is pivotally secured at its rear end between the side arms 42 of the frame 38, as indicated at 44, and this releasing arm 43 is provided with a downwardly-extending, rearwardly-projecting arm 45 which arm terminates in a rearwardly-extending tongue 46, and this rearwardly-extending tongue 46 is pivotally connected to the base 29 by means of a swiveled screw 47 so as to allow the device to be swung and moved slightly upwardly in order to release the track instrument from the rail. A spring trigger 48 is secured to the rearwardly-projecting tongue 46, and this spring trigger 48 is provided with an enlarged depending finger 49 which finger is adapted to fit in one of the notches 31, so as to hold the track instrument at the desired angle relative to the approaching train. It will be seen that owing to the notches 31, the track instrument may be either set to extend exactly parallel with the rail 41, or may be set to extend at an angle to either side of the rail to accommodate the receiving apparatus which is carried by the locomotive.

The framework 38 carries at its upper end a link arm 50, which link arm is pivotally secured to the frame and carries at its outer end a depending link arm 51, which link arm 51 is pivotally connected to the forward end of the link arm 50. This arm 51 constitutes a guide for the releasing arm 43, as the releasing arm 43 passes through an aperture 52 formed in the arm 51. The releasing arm 43 carries a collar 53, which is

fixedly secured to the arm by means of an adjustable screw 54, and a coil spring 55 of the desired strength is interposed between the collar 53 and the arm 51 so as to exert 5 an outward pressure upon the arm 51. A detachable head 55' is connected to the forward end of the releasing arm 43 by means of a bolt 56, and this head 55' is preferably formed of an arrow-shape tapered toward 10 its forward end, as illustrated in Fig. 4. The outer end of the releasing arm 43 is squared so as to engage the head and prevent the head from rotating relative to the arm 43.

15 The operation of the device is as follows: The flagman, who retires to the rear of a train which is delayed for some reason, carries the track instrument, as illustrated in Fig. 4, and as soon as he reaches the desired 20 distance from the rear of his train, the flagman at once attaches the track instrument to a rail near a joint with the ends of arms 39 engaging the ends of a rail connection, so as to have the instrument picked up by 25 an approaching locomotive, providing his signals should be disregarded. After the instrument has been placed in engagement with the rail as above set forth, the instrument will then be in position to coöperate 30 with the receiving mechanism carried by the pilot of the locomotive to at once operate the brakes and prevent the locomotive from running by the signal. As soon as the head 35 55 enters the receiving apparatus by separating the jaws 11, the arm 51 will of course yield rearwardly to the position as shown in dotted lines in Fig. 4, and naturally swing the frame 38 also to the position as shown in dotted lines, thereby kicking the 40 trigger arms 34 out of engagement with the fish plates and entirely unlocking the track instrument from the rail. The jaws 11 of the receiving apparatus will then at once close over the rear end of the head 55 and 45 the track instrument will be picked up by the receiving apparatus and will not become injured. At the same time, the valve 22 will have been operated as previously described, thereby applying the air brakes and 50 bringing the locomotive or train to a stop.

From the foregoing description, it will be seen that by use of the present device a train will be prevented from running past the signals of a flagman, even though the 55 condition of the weather should be such as to make seeing of the flagman by the engineer impossible. It will further be seen that, owing to the simple and efficient construction of the device as set forth, the cost 60 of the manufacture of the article will be reduced to the minimum, and also that, owing to the fact that the track instrument will be picked up by the locomotive, no damage whatever will be done to either the instrument or the receiving device, thereby

making it possible to use the device any number of times. It should also be further obvious that owing to the manner of constructing the present device, all of the parts will act immediately, and without any 70 hesitancy so as to cause the efficient operation of the mechanism. Of course, it should be understood that the receiving apparatus is so formed as to accommodate the swing of the engine as the same is traveling at high speed, so as to allow the head 75 55 of the track instrument to engage the jaws 11 at any time so as to operate the device.

What I claim as my invention is:

1. In a device of the class described, the combination with a receiving mechanism carried by a train comprising a framework having yieldable jaws, of a track instrument detachably secured to a rail and said yieldable jaws adapted to engage said track instrument for lifting said track instrument from a rail.

2. In a device of the class described, the combination with a support carried by a train, of a framework carried thereby, a plurality of jaws carried by said framework normally held in a closed position, one of said jaws being slidably mounted upon said framework and adapted to move upwardly, spring 80 means engaging said last named jaw and said framework for normally holding the jaw in a closed position, an air brake controlling valve positioned in the rear of said jaws, a controlling arm carried by said valve, a projecting arm carried by said slidably-mounted jaw and adapted to engage said arm carried by said valve for operating the same and causing said air brakes to be operated when said slidably-mounted jaw is moved upwardly, and means adapted to be carried by a rail for engaging said jaws for operating said slidably-mounted jaw, and said jaws adapted to grip said means carried by said rail for picking said last- 85 mentioned means up.

3. In a device of the class described, the combination with a support carried by a car, of a framework carried by said support, said framework comprising a pair of divergently-extending arms terminating in upwardly-extending parallel arms, means for securing said upwardly extending arms together, a pair of jaws positioned between said upwardly extending arms, means for holding 115 one of said jaws in a set position relative to said upwardly extending arms, a pair of spring-engaging arms carried by the other jaw, said other jaw slidably mounted between said parallel arms, spring means engaging said spring-engaging arms and said framework for holding said jaws together, said jaws provided with means for directing 120 an object toward the center thereof, a track instrument adapted to be carried by a rail 125 130

for engaging said jaws and spreading said jaws apart, and brake-throwing mechanism coöperating with said slidably-mounted jaw for operating the brakes as said jaw is slid upon said parallel arms.

4. In a device of the class described, the combination with a support carried by a train, of a framework carried by said support, a pair of track instrument gripping jaws carried by said framework, one of said jaws being slidably mounted upon said framework, said jaws provided with notches formed intermediate their side edges having sloping sides, a track instrument adapted to be carried by a rail adapted to engage said notches for spreading said jaws apart, and brake operating means coöperating with said slidably-mounted jaw for throwing the brakes of a train.
5. In a device of the class described the combination with brake operating mechanism carried by a train, of a track instrument comprising a base adapted to be removably attached to a rail, a frame resting upon said base, a releasing arm pivotally connected to the base and capable of swinging upwardly, triggers carried by the base and engaging the frame and a rail to hold the base to the rail, a link connected to the frame, a depending arm carried by the link and through which the releasing arm extends, and a head carried by the releasing arm for engaging and operating the brake mechanism and to cause said brake mechanism to actuate the frame to release the triggers from the rail.
6. A track instrument comprising a base, a framework resting upon said base, a releasing arm pivotally secured to said framework provided with a depending rearwardly-extending arm pivotally secured to said base and capable of swinging upwardly, a link straddling said releasing arm and engaging the upper end of said frame for causing said frame to swing backwardly relative to said releasing arm, and trigger means for engaging the lower end of said framework and adapted to engage a rail for normally holding said track instrument in engagement with a rail.

7. A track instrument comprising a base adapted to fit over a rail, a frame carried by said base provided with laterally-extending bifurcated feet, depending angle arms

carried by said base, a releasing arm carried by said base and capable of having vertical movement, triggers carried by said depending angle arms and engaging said bifurcated feet of said frame, and provided with inwardly-extending fingers adapted to engage a rail for holding said track instrument against longitudinal movement relative to said rail, a link carried by said frame and slidably mounted over said releasing arm whereby said frame will be swung upon said releasing arm for kicking said triggers out of engagement with said rail.

8. A track instrument of the class described, comprising a base, said base provided with a plurality of depending angle arms, triggers carried by said angle arms and provided with inwardly projecting fingers adapted to engage a support, upwardly extending fingers carried by said triggers, a releasing arm secured to said base, and co-operating with said upwardly extending fingers, said base provided with a plurality of notches at its rear end, said releasing arm adapted to engage one of said notches for holding the same in adjusted position relative to the longitudinal axis of said base, and a yieldable buffer carried by said releasing arm.

9. A track instrument of the class described, comprising a base, means for securing said base to a rail, a releasing arm capable of swinging vertically, a frame carried by the base and pivotally supporting said releasing arm, a link member connected to the upper end of said frame, a depending arm pivotally connected to the outer end of said link member, a spring fixedly secured to said releasing arm and exerting an outward pressure upon said depending arm and constituting a yieldable support therefor, an arrow-shaped head carried by the forward end of said releasing arm, and means carried by the rear end of said base and engaging said releasing arm for holding the same in an adjusted position relative to the longitudinal axis of said base.

In testimony whereof I hereunto affix my signature in presence of two witnesses.

LEONARD L. BROWN.
